Benj^m Joseph

United States Patent Office.

BENJAMIN JOSEPH, OF PHILADELPHIA, PENNSYLVANIA, ASSIGNOR TO HIMSELF AND WILLIAM McNIECE, OF SAME PLACE.

Letters Patent No. 79,281, dated June 23, 1868.

IMPROVED PESSARY.

The Schedule referred to in these Letters Patent and making part of the same.

TO ALL WHOM IT MAY CONCERN:

Be it known that I, BENJAMIN JOSEPH, of Philadelphia, and State of Pennsylvania, have invented a new and useful Rectal Pessary for *prolapsus ani*; and I do hereby declare that the following is a full, clear, and exact description of the construction and application of the same, reference being had to the accompanying drawings, and to the letters marked thereon.

Figure 1 is a view of the pessary complete.

Figure 2 is a vertical section.

Figure 3 is a vertical section when covered with a soft substance.

Similar letters in the drawings refer to like parts.

The nature of my invention consists of a hollow ovoidal body, traversed longitudinally by a tubular shaft. The lower end is connected to a piece at right angles, and fitted with a ball-and-socket or universal joint.

To enable others to construct my improved pessary, I will proceed to describe the construction of the same, reference being had to the drawings.

A represents the ovoidal body, and may be made of wood, gutta percha, ivory, or any other suitable substance. c is the vertical shaft, having a central hole through its entire length. On the lower end is a ball, d. At each end of the body A are caps e e. These caps and ball d are fitted to the vertical shaft or tube by means of a screw-thread. This shaft, caps, and ball should be made of ivory, hard rubber, or other suitable hard substances. The body and shaft may be made in one piece, of vulcanized or hard rubber, if desirable.

B should be made of ivory or hard rubber, convex on the upper surface, and concave on the lower. The hole for the ball, countersunk from the lower side, forms a universal joint.

The drawings are full size, yet it may be desirable to make them both larger and smaller. All the parts must be highly polished to avoid irritation.

The application of the instrument is as follows: The body A is introduced into the rectum after the prolapsed portion has been returned to its normal position. The lower part of the vertical shaft or tube c rests upon the *sphincter ani* muscle, and the body of the instrument then prevents the walls of the rectum from collapsing. The short end of the base, B, is placed towards the coccyx, while the long end occupies the perineum, and prevents the body of the instrument from ascending above the point where its support is needed.

The ball-and-socket joint admits of motion in every direction. The hollow tube or central passage admits the discharge of gas or wind.

When it is desirable to cover the body A with some soft substance, such as buck-skin or sponge, that a medical agent may be used in connection with it, the body A should be made as shown in fig. 3.

Claims.

1. I claim the hollow vertical shaft c, in combination with the body A, as and for the above-described purpose.
2. I claim the combination of the base, B, shaft c, and universal joint d, as and for the above-described purpose.

BENJ'N JOSEPH.
